UNITED STATES PATENT OFFICE.

EDGAR B. SYMONS, OF CHICAGO, ILLINOIS.

ROTATING-RING CRUSHING-MACHINE.

1,264,347.

Specification of Letters Patent. Patented Apr. 30, 1918.

Application filed November 9, 1914. Serial No. 870,997.

To all whom it may concern:

Be it known that I, EDGAR B. SYMONS, a citizen of the United States, residing at Chicago, in the county of Cook and State of Illinois, have invented a certain new and useful Improvement in Rotating-Ring Crushing-Machines, of which the following is a specification.

My invention relates primarily to crushing or fine reduction machines wherein the material is to be pulverized or very finely reduced. In order to produce this result, and in order to do it rapidly, it is necessary that the material be spread or arranged on the crushing surfaces in the form of a thin layer or film prior to and during the process of crushing, and this necessitates in the peculiar form of roller ring and crushing machine which I have shown, a ring in which the discharge side or sides are completely open and free to discharge the material at all times absolutely without hindrance. That is to say, the presence of a screen or a selective member of any kind whatever would interfere with the operation of my device by causing a banking up of the crushed material at the screen, and thus the film so necessary would no longer be had.

In my device, therefore, I have provided an arrangement wherein the diameter of the exit opening, that is to say, the diameter at the extreme ends of the crushing ring is effectively equal to the diameter of the ring at that point.

If this thin film is to be maintained, it is necessary to provide some kind of conveying mechanism to convey the material along the crushing surface as it is being crushed, or between successive crushing blows, because the crushing element itself cannot be relied upon satisfactorily to feed the material, and this feed is necessary to prevent banking up and preserve the film of uniform and predetermined thickness.

My invention therefore relates to improvements in rotating ring crushing machines. It is illustrated more or less diagrammatically in one form in the accompanying drawings, wherein

Figure 1 is an end elevation in part section with parts broken away;

Fig. 2 a section on the line 2—2 of Fig. 1;

Fig. 3 a fragmentary detailed plan view of the spreader;

Fig. 4 a detail;

Fig. 5 is a section through another form of my device; Fig. 6 a plan view of the scraper used in Fig. 5; Fig. 7 is a side elevation with parts in section and parts removed of the scraper used in the device of Fig. 5.

Like parts are indicated by the same letters in all the figures.

A is a base block or frame made preferably of concrete, though it might be made of any other suitable material, containing a hopper chamber A¹, a discharge passage A² for the crushed material and a manhole A³ in the wall thereof. Resting on opposite sides of the block A are saddles B, B containing the bearing sleeves B¹, B¹, in which bearing sleeves are located bearings B² to support the single horizontal shaft B³ which has at one end the driving pulley B⁴ driven by any suitable source of power not here shown.

C, C¹ are two cylindrical supporting connections inwardly tapered to receive the wedge blocks C², C³ which are drawn toward one another to wedge between the roll sections C, C¹ and the shaft B³ by means of the bolts C⁴ and nuts C⁵. Keyway C⁶ is provided for the engagement of a key not here shown, to prevent rotation of the wedge blocks and roll sections upon the shaft. D is a two-part crushing ring, the two parts of which are held together by means of the tie bolts D¹ and nuts D² on diametrically opposed sides thereof. This ring is provided about its periphery with flange D³, which is in engagement with the grooved rolls D⁴, D⁵ mounted in bearings D⁶, D⁷ on the support A. The roll D⁴ is free to rotate but is held against longitudinal movement, whereas the roll D⁵ is free to rotate and also to move longitudinally with its axis through a slight excursion between fixed limits. D⁸, D⁹, D¹⁰ are annular crushing ring lining members within the crushing ring and attached therein in any suitable manner. They may be either made up as single annular members or of segments as the case may be. They are, as here shown, held in position against longitudinal movement along the

ring at one side by an annular collar E , at the other side by an annular collar E^1 , which collar forms a base for the outwardly and then inwardly disposed feed ring E^2 , which 5 ring incloses a feed pocket E^3 at one side of the crushing zone. E^4 is a feed spout discharging the material to be crushed into the feed pocket E^3 . E^5 is an adjustable spreader supported on two hinged arms E^6 , E^7 and is 10 made up of one rigid fixed crossbar E^8 to which are pivoted the guide plates E^9 . E^{11} is an adjustable cross bar supported on the arms E^6 , E^7 and held adjustable in position thereon by means of the bolts E^{12} . This 15 crossbar is provided with curved slots E^{13} so that it may be moved longitudinally to adjust the inclination of the guide plates E^9 which are each secured to the crossbar E^{11} by the nuts E^{14} engaging slots E^{15} in the 20 crossbar itself so that each individual guide plate may be adjusted with respect to the remainder or with respect to the movable crossbar itself.

25 F , F^1 are pulleys carrying chains F^2 , F^3 supporting the free ends of the arms E^6 , E^7 . These pulleys are mounted on shafts F^4 , F^5 , controlled by chains F^6 , F^7 over pulleys F^8 , F^9 adapted to be operated and controlled by any suitable means as for example the rod 30 F^{10} and nut F^{11} to raise and lower the spreader and thus control the thickness of film left between the bottom of the guide plates and the crushing ring. Either chain F^6 or F^7 may be dispensed with.

35 In the modification shown in Fig. 5, the ring is centrally hollowed at G^0 to adapt the machine for crushing from relatively large sizes down to relatively small sizes. This hollowing out of the inner surface of the 40 ring may take any form or shape. I have suggested the structure shown in Fig. 5.

With such an apparatus it is necessary, and with any form of ring it might be desirable to spread the material from the center outwardly in either or both directions. 45 This is accomplished by a structure such as that shown wherein the spreading plate E^9 , E^9 are arranged on one side at one angle and on the other side at the opposite angle. 50 To do this effectively, I provide separated bars G , G^1 , each secured preferably by means of a slot and pin G to the side bars E^6 and E^7 . The two bars G , G^1 are secured together by a link G^8 by means of the slots 55 G^4 , G^4 and set screws G^6 , G^5 whereby the two bars G and G^1 are adjustable to and from each other. They are mounted so as to be downwardly inclined toward the middle line of the ring. Each of the 60 spreader plates is preferably secured to its proper cross bar G^1 by means of the arc-shaped slot and set screw G^6 so that the individual spreaders may be separately adjusted. G^7 is a short link which connects 65 the two bars G^8 , G^8 to which the other ends

of the spreaders E^9 are pivoted. By this means the spreaders may be adjusted in any desired manner to accommodate themselves to the service required in connection with a ring where the material is fed near the middle and to a ring whose surface is inwardly hollowed out. G^9 is an inward extension of the feed-spout which delivers near the middle line of the ring and at one side of the spreader device. 70

It will be evident that while I have shown in my drawings an operative device, still many changes might be made in size, shape and arrangement of parts without departing from the spirit of my invention. I wish, 80 therefore, that my drawings be taken as in a sense diagrammatic, and I do not wish to be limited to the particular devices shown or to the particular elements of the machine accompanying the essential features of my invention. 85

The use and operation of my invention are as follows:

The crushing machine is started by rotating the shaft in the usual manner. This 90 causes the ring to rotate, since the ring is supported on the roll. The material to be crushed is then fed in through the feed spout and discharged into the annular feed pocket at one side of the ring. When this pocket is 95 filled, the material piles up and is then reached by the first guide plate, which, acting as a plow or guide, feeds the material over into the crushing zone. The material, of course, as it falls into the feed pocket and 100 is fed into the crushing zone is held by centrifugal force against the inner surface of the ring, is carried around and when in the feeding zone, is acted upon by the crushing roll, being crushed thereby, the weight of 105 the ring crushing the material against the roll as an anvil. The material after being crushed comes around and strikes the next guide plate and is by it moved slightly over. It goes up and is again crushed and comes 110 down and strikes the next guide plate. This continues until the material has passed completely through the ring, making as many complete revolutions to make this passage as there are guide plates. The material is 115 pushed off the ring at the bottom on the side opposite the side at which it enters, and is discharged by centrifugal force downwardly into the receiving hopper.

It will be understood that as the coarse 120 material is fed in at one side of the ring, it may occupy more space than the fine material which is discharged, and since the roll and ring are designed normally to rotate about parallel axes, it is necessary either 125 to increase the amount of material as it passes through the ring or else to decrease the distance between the ring and roll toward the discharge end.

It will be noted that I have made provi- 130

sion for both means of adjustment. I have shown the inside diameter of the ring slightly larger at the feed end than it is at the discharge end so that as the material 5 by being reduced packs down and occupies less space, it will still always be crushed by the ring. If this adjustment is not sufficient, and under some circumstances it might be insufficient, it is only necessary to adjust 10 the guide plates so that each successive plate is more nearly parallel with a plane perpendicular to the axis of rotation so that each vein feeds the material forward a shorter distance. The result of this will, 15 of course, be to have the material bank up to a certain extent so that more material will be in the ring toward the discharge end than is in it adjacent the feed end, and this will compensate for the decreased bulk of 20 the finely crushed material as contrasted with the coarser material.

When my device is in operation with the rotary speed of the ring sufficient to cause a blanket of material to adhere firmly to it, 25 it is obvious that so long as the ring rotates at the necessary speed, the force of gravity or any other force can exert no influence to change the position of the material on the ring, because the only other force present 30 and unaccounted for is the crushing force exerted between the crushing surfaces on the ring and on the roll which tends to make the two crushing surfaces taken at the crushing point first approach to and then recede 35 from each other and since the angle of approach is very great, the material is smoothly and easily rolled down and compacted into a flat firm mass by the pressure between the two surfaces. This action both compacts 40 the whole blanket of material on the ring and also compacts individual particles into hard brick-like slabs or cakes made up of crushed or powdered material compacted together by the pressure, and it is necessary 45 if the crushing is to proceed that this blanket be broken up and that these hard cakes be cracked or disturbed to again expose them to the crushing pressure between each successive crushing stroke to prevent 50 the blanket material and particularly such hard cakes acting as a cushion to protect the uncrushed particles from being crushed. It is also necessary to move this material progressively or gradually along to feed it 55 through the machine, and the feeding vanes which I have shown thus have a two-fold function, first, to act as a stirring or agitating harrow-like teeth to scrape up and agitate the crushed blanket, and second, to 60 act as conveyer blades to move the crushed material through the machine.

I have talked about movements of the crushing surfaces or successive movements of the crushing surfaces. It will be obvious 65 that the crushing surfaces in *toto* remain

always at substantially the same position but since they rotate about different axes and since their peripheries are substantially tangential, it is obvious that they do effectively at least have a movement and do in 70 effect have or form a crushing stroke since any point of the surfaces will gradually or successively approach it and recede from the other surface.

It will be understood that the arrangement which I propose provides means for reducing the material by a series of successive separate crushing hammer-like blows, that is to say, while the crushing ring and crushing roll are always in contact, still any 80 one point on the crushing ring is treated by a series of successive blows, one blow occurring each revolution of that point when it passes the roll.

I claim:

1. A crushing machine comprising a ring, a roll within and supporting it, means for rotating the roll, means for feeding the material to the surface of the ring, means for feeding the material to the surface of the 90 ring near its middle line and a spreading device to move the material outwardly from its middle line toward both sides of the ring.

2. A crushing machine comprising a ring, a roll within and supporting it, means for 95 rotating the roll, means for feeding the material to the surface of the ring, means for feeding the material to the surface of the ring near its middle line and a spreading device to move the material outwardly from 100 its middle line toward both sides of the ring, said ring hollowed from near its middle line outwardly.

3. A crushing machine comprising a ring, a roll within and supporting it and means 105 for rotating the roll, and means for feeding the material to be crushed transversely across the crushing face of the ring by a series of separate steps, said steps being shorter adjacent the discharge side of the 110 ring.

4. A crushing machine comprising a ring, a roll within and supporting it and means for rotating the roll, and means for feeding the material to be crushed transversely 115 across the crushing face of the ring by a series of separate steps, said steps being progressively diminished from the feed to the discharge point.

5. A crushing machine comprising a pair 120 of opposed crushing surfaces, means for moving them toward and from one another, means for feeding material to them and means for conveying it gradually across them by a series of separate movements of 125 progressively diminishing length between the movements of the crushing members.

6. A crushing machine comprising a pair of opposed crushing surfaces, means for moving them toward and from one another, 130

means for feeding material to them and means removed from the effective crushing zone between the surfaces for conveying the material gradually across them by a series 5 of separate movements of progressively diminishing length between the movements of the crushing members.

7. In a crushing machine a pair of opposed crushing surfaces, means for moving 10 them to and from one another to give a crushing stroke, means for feeding material

to said surfaces and means for propelling it with gradually decreasing velocity controllably along said crushing surfaces.

In testimony whereof, I affix my signature 15 in the presence of two witnesses this 30th day of October, 1914.

EDGAR B. SYMONS.
